UNITED STATES PATENT OFFICE.

PHILIP M. HAAS, OF YOUNGSTOWN, OHIO, AND FRANK M. NAIR, OF BEAVER FALLS, PENNSYLVANIA.

BAR-CUTTING MACHINE.

1,273,775.

Specification of Letters Patent.

Patented July 23, 1918.

Application filed October 1, 1917. Serial No. 194,123.

To all whom it may concern:

Be it known that we, PHILIP M. HAAS and FRANK M. NAIR, citizens of the United States, residing, respectively, at Youngstown, in the county of Mahoning and State of Ohio, and at Beaver Falls, in the county of Beaver and State of Pennsylvania, have invented certain new and useful Improvements in Bar-Cutting Machines, of which 10 the following is a specification.

The invention relates to a machine for transversely cutting a bar for dividing it into sections of desired lengths; and the object of the invention is to provide a rotary head for clamping and rotating the bar for cutting, with means for releasing the bar for feeding it endwise through the head.

A preferred embodiment of the invention is illustrated in the accompanying drawings 20 forming part hereof, in which—

Figure 1 is a side elevation of the bar cutting machine, showing the rotary head and clamping means in section, on line A—A, Fig. 3;

Fig. 2, a side elevation of the clamp operating means, showing the rotary head in section, on line A—A, Fig. 3;

Fig. 3, a plan view of the clamp operating means showing the rotary head in section, on line B—B, Figs. 1 and 2;

Fig. 4, an end elevation of the rotary head;

Fig. 5, a detached perspective view of one jaw; and

Fig. 6, a detached perspective view of one jaw bushing.

Similar numerals refer to similar parts throughout the drawings.

Upon the base 1 of the machine are mounted 40 suitable journal bearings 2 and 2^a, for the hollow shaft or cylindric sleeve 3, on one end of which sleeve is secured a suitable gear wheel 4 by means of which the cylindric sleeve may be rotated in the journal bearings.

The other end, herein referred to as the forward end, of the cylindric sleeve is enlarged in diameter and is provided with the counter-bore 5 in which is located the idle 50 sleeve 6, which is freely rotatable in the counter-bore and has an inside diameter substantially equal to that of the cylindric sleeve, forming a clear through passage for receiving a bar for cutting.

55 The same end of the cylindric sleeve is

provided with the larger counter-bore 7 in which is located the pair of semi-cylindric jaws 8, which jaws are provided with the internal annular L-flanges 9 on their rear ends interengaging with the external L-flanges 10 on the forward end of the idle sleeve 6, thus forming a swivel connection between these parts.

The external annular groove 11 is provided at the rear end of the idle sleeve 6, in which are freely engaged the short arms 12 of the bell cranks 13 which are journaled on the shafts 14 mounted in the ears 15 provided on diametrically opposite sides of the cylindric sleeve 3, which sleeve is provided with the slots 16 located between said ears to receive the hubs and shorter arms of the bell cranks 13.

The longer arms 17 of the bell cranks extend alongside the cylindric sleeve at a free interval therefrom, and their free ends are connected by their pivots 18 with the inner ends of the outwardly extending links 19, and the outer ends of these links are in turn connected by the pivots 20 with the outer ends of the radial arms 21 which are formed or secured on the collar 22 which is swiveled or journaled on the cylindric sleeve 3, and is adapted to slide longitudinally thereon.

The slide collar 22 is provided with the external annular groove 23 in which is journaled or swiveled the collar 24 having the trunnions 25 on diametrically opposite sides, which trunnions are journaled in the bearings 26 formed or secured on the ends of the yoke arms 27 which are keyed on the rock shaft 28 journaled in the bearings 29 mounted on the base 1 of the machine; on one end of which rock shaft is likewise keyed the operating lever 30 by means of which the idle sleeve 6 and the clamp jaws 8 swiveled thereon may be moved longitudinally in the counter-bore of the cylindric sleeve 3.

Each semi-cylindric jaw 8, is slightly tapered externally from a larger diameter at its rear end 8^a to its forward end 8^b, and at the middle of the side of the forward end of each jaw is provided the square block 31, having a flat face 32 beveled or inclined outward from front to rear; and upon the edge sides at the same end of each semi-cylindric jaw are provided the square blocks 33, having their faces 34 formed parallel with the axis of the jaw and also parallel with the sides of the beveled blocks 31.

Upon the forward end of the cylindric sleeve 3 is secured the cap or head 35, as by screwing the flange 36 upon the end 37 of the sleeve; by means of which screw connection 5 the head may be adjusted endwise on the sleeve, and the head be fixed in any position of adjustment by means of the lock nut 38, which is in the form of a collar screwed upon the end of the sleeve inside the screw 10 flange 36 of the head.

The head 35 is provided with a suitable annular opening 39 for receiving the forward ends of the jaws when the same are spaced slightly apart as shown in Fig. 4; 15 and in the sides of this opening are cut the longitudinal channels 40 and 41 for receiving the blocks 31 and 33 on the jaws. The bottoms 42 of the channels 40, are formed flat and are beveled or inclined in correspondence with the beveled flat faces of the blocks 31, and the bottoms 43 of the channels 41 are formed in a plane parallel with the axis of the head, which blocks and channels coöperate to stop the jaws from rotating 20 with respect to the head, while permitting them to slide endwise therein.

The forward ends 8^b of the jaws 8, are normally held slightly spaced apart, by means of the coil springs 44 located in the 30 recesses 45 provided at the sides of the jaws adjacent to the forward end thereof, and it is evident that by an endwise forward movement of the jaws in the head, the jaws will be forced together by reason of the wedge action 35 of the beveled flat faces 32 of the blocks 31 operating against the reversely beveled flat abutments formed by the bottoms 42 of the recesses 40 in the head; and that an endwise rearward movement of the jaws will permit 40 the action of the springs 44 to force the forward ends of the jaws apart, as shown in Figs. 2 and 4.

Suitable semicircular bushings 46 are detachably located in the forward ends of the 45 jaws, and the inner faces 47 of these bushings are suitably formed and shaped for engaging the particular bar to be cut. The bushings are held against endwise movement in the jaws, by means of the annular ribs 50 50 engaging with corresponding grooves 49 provided therefor in the jaws; and the bushings are furthermore secured to the jaws by means of the cap screws 50, which may be entered through suitable apertures 51 55 provided in the cap or head of the machine.

In the operation of the machine, bushings for engaging the bar are secured in the jaws and the bar to be cut is entered from the rear, endwise through the hollow shaft or 60 cylindric sleeve 3, until its forward end protrudes through and beyond the clamping jaws; and a suitable stop 52 is preferably mounted upon the base 1 of the machine, against which the forward end of the bar 65 may abut for making a cut of the desired

length by means of a cutting tool 53 likewise mounted upon the base of the machine.

When the first bar of a given size or diameter is placed in the machine, the cap or head thereof is adjusted by screwing upon the 70 end of the cylindric sleeve, until the jaw bushings are clamped upon the bar, after which the head is given a slight turn in the reverse direction for releasing the bar and is then locked in position by means of 75 the nut 38; this adjustment being made when the operating lever is rotated to the left or rearward as shown in Fig. 2 which draws the jaws into their rearmost or releasing position shown in the same figure. In this 80 position, the bar is free to move between the jaws, or in other words, the jaws are free to rotate without turning the bar, which permits the bar to be inserted in the machine without stopping the rotation of the cylindric sleeve and clamping jaws therein.

When it is desired to make a cut, the bar having been pushed into proper position with its forward end against the stop 53, the operating lever 30 is pulled to the right or 90 forward, which carries the slide collar 22 and the links 19 forward and swings the free ends of the long arms 17 of the bell cranks 13 inward and the short arms 11 thereof forward, thus sliding the idle sleeve 6 and 95 the jaws 8 forward and clamping the jaw bushings upon the bar by action of the wedge blocks 31 in the inclined channels 40 of the head; it being understood that in this position, the outer ends of the links 19 are 100 carried forward beyond the inner ends thereof, thus locking the mechanism in clamped position.

Upon the completion of the cut, the operating lever is swung to the left or rearward, thereby releasing the jaws from the bar which may then be pushed forward again in 105 position for another cut without stopping the operation of the machine; it being understood that either the swivel connection between the jaws 8 and the idle sleeve 6 or the swivel connection between the idle sleeve 6 and the arms 5 of the bell crank, serves to permit the continuous rotation of the jaws with reference to the operating means by 110 which the jaws are moved forward and rearward for clamping or releasing the bar, (it being immaterial as to which of these swivelled joints is brought into play), so that the idle sleeve may either rotate with the jaws 115 or not, without affecting the operation of the machine.

The cylindric jaws 8 and the adjoining and adjacent parts are so shaped and proportioned that the rear ends are free to separate with the forward ends, as shown in 125 Fig. 2, and it is evident that the full extent of the beveled flat faces 32 on the jaws will be acted upon by the abutting beveled flat bottoms 42 of the head recesses, through- 130

out the whole extent thereof, thus clamping the full length of the jaw bushing 46 against the bar and holding the same more rigid than would be possible if the jaws did not 5 operate bodily to and from each other throughout their length.

We claim:—

1. A bar cutting machine having a rotary sleeve, semi-cylindric jaws in the end of the sleeve having square blocks with beveled flat faces on the sides of their forward ends, springs for normally separating the same ends of the jaws, a head on the forward end of the sleeve having an opening for the 10 jaws and channels with beveled flat bottoms for the beveled blocks, and means for sliding the jaws endwise in the head for clamping together their forward ends by the wedge action of the beveled blocks.
2. A bar cutting machine having a rotary sleeve, semi-cylindric jaws in the end of the sleeve having square blocks with beveled flat faces on the sides of their forward ends, springs for normally separating the same 15 ends of the jaws, an adjustable head on the forward end of the sleeve having an opening for the jaws and channels with beveled flat bottoms for the beveled blocks, means for locking the head in a given position, and means for sliding the jaws endwise in the head for clamping together their forward ends by the wedge action of the beveled blocks.
3. A bar cutting machine having a rotary sleeve, semi-cylindric jaws in the end of the sleeve having square blocks with beveled flat faces on the sides of their forward ends, springs for normally separating the same ends of the jaws, a head on the 20 forward end of the sleeve having an opening for the jaws, and channels with beveled flat bottoms for the beveled blocks, and means for sliding the jaws endwise in the head for clamping together their forward ends by the wedge action of the beveled blocks.

blocks, said means including lever and link connections automatically locking the jaws in clamped position.

4. A bar cutting machine having a rotary sleeve with an idle sleeve rotatable therein, 50 semi-cylindric jaws swiveled on the end of the idle sleeve and having square blocks with beveled flat faces on the sides of their forward ends, springs for normally separating the same ends of the jaws, a head on the forward end of the rotatable sleeve having an opening for the jaws and channels with beveled flat bottoms for the beveled blocks, and means for sliding the idle sleeve endwise for clamping together their forward ends by the wedge action of the beveled blocks.

5. A bar cutting machine having a rotary sleeve, semi-cylindric jaws in the end of the sleeve, adapted to be bodily separated 65 throughout their length therein and having square blocks with beveled flat faces on their sides, a head on the forward end of the sleeve having an opening for the jaws and channels with beveled flat bottoms for 70 the beveled blocks, and means for sliding the jaws endwise in the head for clamping them together by the wedge action of the beveled blocks.

6. A bar cutting machine having a rotary 75 sleeve, semi-cylindric jaws in the end of the sleeve adapted to be bodily separated throughout their length therein and having blocks with beveled flat faces on their sides, a head on the forward end of the sleeve having an opening for the jaws and beveled flat abutments for the beveled blocks, means for stopping the rotation of the jaws with respect to the head, and means for sliding the jaws endwise in the head for clamping 80 85 them together by the wedge action of the beveled blocks.
